UNITED STATES PATENT OFFICE.

HARRY VICTOR MAJOR, OF LONDON, ENGLAND, ASSIGNOR TO SAMUEL JONES AND COMPANY LIMITED, OF LONDON, ENGLAND.

GUM BOTTLE AND THE LIKE.

Application filed November 29, 1924. Serial No. 753,000.

To all whom it may concern:

Be it known that I, HARRY VICTOR MAJOR, a British subject, residing at 16 Derwent Road, Anerley, London, S. E. 20, England, have invented certain new and useful Improvements in Gum Bottles and the like, of which the following is a specification.

This invention relates to stoppers, nozzles and the like and in particular refers to an improved cap to be applied to bottles of gum or other suitable fluid.

It is an object of the present invention to provide an improved device including a slot or the equivalent which is normally closed by a lip, but is automatically opened to permit of the flow of the fluid to a greater or less degree according to the pressure exerted by the user when applying the fluid to the articles or surface to be coated therewith. Other objects of the invention comprise the provision of the improved features, combinations and arrangements embodied in the preferred form of apparatus hereinafter described with reference to a cap for gum bottles and specifically claimed.

Referring to the drawings:—

Fig. 1 is a view showing the device in position for use.

Fig. 2 is a plan view of the gum bottle.

Fig. 3 is a sectional elevation of the upper part of the device with a stopper inserted in the bottle for transport.

Fig. 4 is a sectional view to an enlarged scale of the upper part of the nozzle.

Fig. 5 is a view to the scale of Fig. 4 showing how the aperture in the nozzle may be forced open by side pressure if necessary.

As illustrated, the bottle generally designated by the reference A adapted to contain the gum or the like is provided with a rubber cap B fitting securely upon its neck. For convenience in operation, one side of the cap presents a flat surface 1 which is more or less parallel with the adjacent side of the bottle. At the upper end of this surface and slightly inset from it a horizontal slot 2 is formed and the opposite side of the cap is curved round and terminates in a lip 3 which overhangs the slot and is preferably tapered and provided with a serrated edge 4 for easy application of the gum. The lip normally springs down and keeps the slot closed and sealed.

In use the cap B may be applied to the

exterior of the neck 5 of the bottle and a cork or stopper 6 may be inserted on the inside of the neck for greater safety during transit. When it is desired to apply the gum the cap is removed, the cork extracted and the cap replaced securely on the neck of the bottle. To apply the gum the bottle is turned a little bit past the horizontal position and the lip drawn lightly across the surface to be gummed. The flow of the gum is regulated by the pressure exerted on the lip and as soon as pressure is removed the lip springs down and seals the aperture. If the device has not been used for a considerable time the aperture may be opened by applying pressure at either side of it, as indicated at Fig. 5, and, if considered necessary the cap may be removed and cleaned by dropping it into water. The term "slot" is to be read hereinafter to include any form of aperture or combination of apertures functioning in the manner of the slot herein described.

It is to be particularly noted that the flat surface 1 is adjacent its juncture with the lip 3 slightly offset from the plane of the flat surface, and that the lip 3 is in effect a continuation of the curved wall of the cap B and is arranged immediately adjacent this offset portion. As the slot 2 is formed in this offset portion, it will be apparent that pressure upon the lip will act immediately upon the weakened portion of the flat surface 1, that is, the offset part in which the slot 2 is formed. Thus the slot will open more readily under pressure on the lip than if such lip were thickened and the slot formed in a portion of normal thickness, for in such case, the tendency of pressure on the lip would be to direct the bending action at the end of the lip, and the opening of the slot would respond only to sufficient pressure to overcome the bending tendency of the remote wall.

It will be further noted that the free edge of the lip is serrated in order to provide for proper spreading of the material, and if a comparatively heavy pressure is required to open the slot 2, the projections forming the serrations will be forced into contact with the surface and the spreading effect of the serrations will be entirely lost. With the arrangement of the slot as described, a comparatively light pressure only is necessary

on the lip 3 to open the slot, and hence the serrations or points remain effective for spreading purposes. Furthermore, the provision of the recessed portion in which the slot is formed provides for the retention in such recess of a small supply of material to draw upon in the initial application of the device.

I claim:

- 10 1. In a closure for a reservoir for fluid, including a cap having a flat wall and a curved wall, the curved wall being extended beyond the flat wall to form a lip, the flat wall adjacent its juncture with the curved wall being slightly offset and formed in such offset portion with a slot, whereby pressure on the lip will be initially directed to the off-

set portion of the flat wall and to opening the slot formed therein.

2. A fluid reservoir closure including a 20 cap having a flat wall and a curved wall, the curved wall being extended beyond the flat wall to form a lip, the free edge of the lip being serrated, the flat wall adjacent its juncture with the curved wall being reduced 25 in thickness to form a recess, and formed in the base of such recess with a slot, whereby to reduce the pressure necessary on the lip to open the slot to a degree to prevent loss of function in the lip serrations under 30 such necessary pressure.

In testimony whereof I affix my signature.

HARRY V. MAJOR.
